UNITED STATES PATENT OFFICE.

SAMUEL W. SKIPWORTH, OF BLUE MOUND, KANSAS.

COMBINED CHIMNEY AND VENTILATOR.

SPECIFICATION forming part of Letters Patent No. 340,379, dated April 20, 1886.

Application filed January 28, 1886. Serial No. 190,088. (No model.)

To all whom it may concern:

Be it known that I, SAMUEL W. SKIPWORTH, a citizen of the United States, and a resident of Blue Mound, Linn county, Kansas, have 5 invented certain Improvements in Combined Chimneys and Ventilators, of which the following is a specification.

My invention relates to that class of combined chimney-flues and ventilators in which 10 the ventilating-flue surrounds the smoke-flue or chimney, my invention comprising certain details in the construction of a device of the this class with the view of rendering it effective in action, simple in construction, and 15 readily applicable to the building in connection with which it is to be used.

In the accompanying drawings, Figure 1 is a 20 sectional view of a building provided with my improved chimney-flue and ventilator; Fig. 2, 25 a perspective view of parts of said chimney-flue and ventilator detached from each other, and Figs. 3 and 4 detached sections of the upper part of the device.

I have shown my invention in the present 25 instance as applied to a house having two stories and an attic; but it will be evident that it may be varied in size to suit houses of different constructions.

The ventilator is made in three sections, A, 30 B, and D, the upper section, A, being above the roof, and having an outer casing, *a*, which may be square or of other suitable form, and painted in imitation of an ordinary brick chimney, and this casing should have at the 35 lower edge a projecting plate, *b*, which is so secured to the roof of the house as to form a water-tight joint.

The section B consists of a cylinder, *d*, having at the top a projecting plate, *e*, also confined to the roof, said cylinder passing down through the attic and upper rooms of the house, and being constructed at the lower end for the reception of the outer cylinder, *f*, of the lower section, D, of the ventilator, this 45 section passing through the floor and ceiling and terminating in the lower room or apartment of the building.

The upper section, A, of the ventilator has a flat top, to which is connected by a water-tight joint the upper end of the smoke-flue, *g*,

which passes down through the casing *a* and cylinder *d*, and receives at the lower end the upper end of a pipe, *h*, forming part of the lower section, D, of the ventilator. The central flue thus provides for the escape of the 55 smoke and products of combustion from stoves or furnaces located in the various rooms of the building, (see, for instance, the dotted lines in Fig. 1,) while the annular chamber or space between said smoke-flue and the outer casing 60 of the ventilator provides for the passage of foul air from the various rooms, this foul air entering the annular space or chamber through suitable valved ventilators, and escaping through openings *i* at the upper end of the 65 casing *a* into a chamber formed within the molding *m*, surrounding the upper end of said casing, from which chamber the air escapes through openings *n* at the bottom.

The upper section, A, of the ventilator has 70 at the top an arched hood, *F*, to prevent the entrance of rain or snow directly into the mouth of the flue *g*, and to prevent rain or snow from driving in from either end of said arched hood, the latter has at each end inclined deflectors *p*, as shown in Fig. 3, these deflectors forming with the hood contracted air-spaces *s*, which serve to direct forcible 75 blasts of air across the hood and in contact with the inner face of the same, so as to prevent the accumulation of soot thereon.

In order to permit access to the flue *g*, for the 80 purpose of cleansing the same when necessary, the hood *F* is hinged at one edge and confined at the opposite edge by a locking pin 85 or key, so that on removing said key the hood can be readily thrown to one side, as shown in Fig. 2, and the mouth of the flue exposed.

By making the ventilator in sections, as described, the manufacture of the same and its 90 application to a building are facilitated, the telescopic joint formed between the sections B and D of the ventilator and between the flue-pipes *g* and *h* permitting the application of the ventilator to houses which vary slightly 95 in the height of the stories, without a special construction of device for this purpose.

I am aware that a ventilator has been proposed in which the upper part of a lower section is fitted into the lower end of an upper 100

section; but in this case telescopic movement was prevented, owing to the fact that the lower section had a top or cap plate extending from the inner to the outer tube, which cap-plate 5 came into contact with the lower end of the inner tube of the upper section. In my improved ventilator there is no such obstacle to the free telescopic movement of the lower section of the ventilator in the upper section.

10 I claim as my invention—

1. The combination, in a combined chimney and ventilator, of the following elements, namely: the top section, A, consisting of a casing, a, the roof-plate b, and the smoke-flue 15 g, secured to the top of the casing, the intermediate section, B, having a roof-plate, e, and tube d, inclosing the flue g, and the lower section, D, having two tubes, f and h, forming a telescopic joint with the tube d and flue g, all 20 substantially as specified.

2. The combination of the top section, A, of the ventilator, consisting of a casing, a, and 25

roof-plate b, the section B, consisting of a tube, d, with roof-plate e, and the smoke-flue g, secured to the top of said upper section and 25 projecting down through the tube d, all substantially as specified.

3. The combination of the top section of a ventilator and the smoke-flue g with the arched hood F and the inclined deflectors p at the 30 ends of the same, all substantially as specified.

4. The combination of the top section, A, and its smoke-flue g with the arched hood F, having at its ends inclined deflectors p, forming contracted air-passages immediately beneath the hood, all substantially as specified. 35

In testimony whereof I have signed my name to this specification in the presence of two subscribing witnesses.

SAMUEL W. SKIPWORTH.
